METHOD OF FORMING AND LAYING CONTINUOUS CONCRETE PIPE.

Application filed March 12, 1921. Serial No. 451,756.

This invention has reference to a method of forming concrete pipes, and its object is to lay such pipes continuously so that they are practically monolithic from one end to 5 the other and may be of any length.

In accordance with this invention, the pipe units are made in relatively short lengths, say, from ten to twenty feet as a maximum; and the ends of the units are united in such 10 manner as to provide a substantially monolithic structure, wherefore the pipe line is in effect a one-piece line, although provision is made for such slippage as may be advisable to prevent buckling or cracking of the 15 cement as it dries and as it is subjected to temperature changes.

It has been the custom heretofore, in laying concrete pipe, to set a gang of men at work and build a length of pipe by the aid 20 of molds or forms, but since concrete pipe must harden for a certain period of time before the mold is removed, the amount of pipe which may be laid in the course of a working day is limited to from 150 to 200 feet, 25 according to the size of the pipe and according to the manner of laying such pipe.

By practicing this invention the amount 30 of pipe which may be laid in the course of a day, may be gradually extended by the use of a sufficient number of forms initially assembled in pairs, with each pair separated from the next pair by relatively long distances and then working from the adjacent 35 ends of companion pairs toward each other.

Because of the necessity of the formed pipe 40 setting for a much longer time than it takes to lay it, a gang of men may attend to several pairs before the laid pipe is sufficiently hard to permit the removal of the molds. In this way, many hundreds or even thousands 45 of feet of pipe may be formed in the course of a day, making the operation very economical. Experience has demonstrated that the pipe so laid is much stronger than pipe heretofore made by any other method.

In accordance with the invention, tamping of the concrete is not practiced and the concrete mixed is initially in the condition known in the art as plastic or sloppy mix 50 thus making the walls of the pipe dense without the necessity of tamping and also producing an intimate union between the lengths of pipe where they come together.

The invention will be best understood 55 from a consideration of the following de-

tailed description taken in connection with the accompanying drawing forming part of this specification, with the understanding, however, that the invention is not confined to any strict conformity with the drawing, 60 but may be changed and modified so long as such changes and modifications mark no material departure from the salient features of the invention as expressed in the appended claims. 65

In the drawings:—

Fig. 1 is a diagrammatic view illustrating the manner of forming the pipe where approaching zones of pipe are produced to be ultimately joined to form monolithic pipe. 70

Fig. 2 is a vertical section through one end of a finished pipe and the succeeding section of an unfinished pipe with a form in place ready for pouring, the arrangement being such as to produce pipe capable of 75 withstanding considerable internal pressure.

Fig. 3 is a longitudinal section through the adjacent approaching ends of two pipes, showing the means of coupling such ends where the coupling is of monolithic character and capable of withstanding considerable 80 internal pressure.

Fig. 4 is a longitudinal vertical section of a form of pipe where considerable internal pressure is not to be resisted. 85

Fig. 5 is a view similar to Fig. 4, but showing a further step in the formation of the joint.

Fig. 6 is a view similar to Fig. 5, but showing further progress in the formation 90 of the joint.

Figs. 7, 8 and 9 are cross sections showing different steps in the formation of the concrete pipe.

Fig. 10 is a cross section through a coupling in which corrugated sheet metal is used. 95

Fig. 11 is a cross section showing the preferred manner of weighting down the mold with rock. 100

Fig. 12 is a cross section of a pipe in which reinforcement is employed.

In accordance with the method of the invention, when preparing to lay the concrete pipe, which it may be assumed is to 105 be laid underground, a trench which may be hundreds or even thousands of feet in length is first excavated.

A suitable number of molds is provided, and these molds are distributed in pairs 110

along the trench ready for use, at distances apart which may amount to 500 or 600 feet, more or less. If the pipe to be made is 12-inch pipe, a gang of about four men is required, which gang can take care of from 5 five to six molds. In order to facilitate the work, water-tight mixing boxes are set up at intervals alongside of the trench and filled with sand, gravel and cement and a little 10 clay. One man of the gang paints a mold and one dresses the trench, while two men mix the dry concrete which is prepared in three batches in each box. The first batch, which in quantity amounts to about one- 15 fourth of the concrete in the mixing box, has water applied thereto to soak the mixture. While the soaking is progressing, the workmen are covering up the pipe, made the day before, with dirt. Then the first 20 fourth of the batch is thoroughly mixed and introduced into the bottom of the trench. The mold is then placed in the trench on top of the first batch and forced down into it for a short distance, whereupon the second 25 batch is mixed and poured upon the first batch about the sides of the mold. Following this, the third batch is mixed but with a less amount of water to make a drier mixture, and is deposited in the trench, finally 30 covering the mold and completing the pipe.

The sloppy or plastic mixture of concrete is such that when the temperature prevailing at the time the pipe is being formed ranges from 60° F. downward, it is necessary 35 to keep the molds from floating on the concrete as it is poured. For this purpose, two large flat rocks or other weights are placed in the bottom of the trench with a piece of wire laid under them and hung 40 up on the side of the trench temporarily out of the way while the bottom layer of concrete is poured. Then, when the mold is set sufficiently, the two ends of each wire are brought together and secured tight 45 around the mold so that the rocks act as weights to keep the mold from floating to the top of the concrete. Such rocks are placed in the bottom of the trench below the concrete and about two feet from either 50 end of the mold and are allowed to remain permanently.

The concrete poured into the trench about the mold and in contact with the ground at the bottom and sides of the trench becomes 55 earth-cured, while the drier mixture completing the pipe absorbs the moisture rising from the two lower layers already poured, thus helping to set the newly made pipe faster than otherwise, and also preventing any water from running along the top 60 of the pipe and destroying the new pipe.

When starting to lay the pipe, two forms or molds are usually employed in end to end engagement, or if there be a bend contemplated in the pipe line, it is customary 65

to start the formation of the pipe at the bend with two molds in abutment. After having completed the two lengths of pipe in end engagement, the gang of workmen goes to the next location, which may be 500 70 or 600 feet away from the first location, and repeats the operation, producing two or more lengths of pipe in line with the first two lengths, or with one of the first two lengths.

While waiting for the second pair of 75 lengths of pipe to set sufficiently, the gang of workmen may lay the third two lengths and so continue the operation throughout the working day. Thus 4 to 6 in. molds may be re-used, say four times in eight 80 hours, when the temperature ranges from 60° F. upward, and 8 in., 10-in. and 12-in. molds may be re-used about three times in eight hours, while all molds from 15-in. upwardly can be re-used twice in eight hours. Hence under the same temperature conditions 85 a very much larger amount of concrete pipe may be formed by the method of this invention than is possible with the methods heretofore employed and with the further 90 advantage that the pipe is far superior.

The operations already described take 95 about one-half a working day, in the formation of 12-in. pipe and proportionately greater or less time with larger or smaller 100 pipe length. By such time, the first laid pipe has set sufficiently to permit the withdrawal of the molds and the latter are reset at the completed ends of the first laid pipe, thereby permitting the formation of further lengths of pipe beyond the first laid ones, thus bringing the pipe line ends closer to the previously laid pipe. This permits the laying of some hundreds of feet of pipe 105 in the course of a working day by a single 110 gang of men.

In using concrete pipe, one of two conditions are met with, the first where the water conducted by the finished pipe merely flows from a source to the point of utilization, 115 without material internal pressure, in which instance the pipe is never full. The other condition is where the flowing water fills the pipe and exerts pressure upon its entire inner surface. In either case, the pipe contracts after it is molded and is afterwards 120 subject to expansion and contraction due to changes in temperature and water will flow out of the pipe at the joints in streams corresponding to the conditions produced by such 125 expansion and contraction. Sometimes where the temperature differences are large, leaks of considerable size may occur unless provision is made to prevent them. Where the pipe lengths range from 10 to 20 feet, slip joints are employed between the sections to avoid the formation of cracks and these slip joints are embedded in the concrete 130 so that small differences in length, due to expansion and contraction, may occur.

without causing either the cracking or the buckling of the concrete. On making a new joint where slip joints occur, the end of the last layer should be painted or oiled to keep 5 the new joint from knitting to the previous joint, thus allowing the slip joint to operate in case of contraction and expansion.

Preliminary to laying the pipe, there is 10 formed a trench 1 provided with a rounded bottom 2 (Figs. 7, 8 and 9) into which a layer 3 of concrete is poured to a depth so that when a form or mold 4 is set in the trench and the concrete is poured between the mold and the walls of the trench it rises 15 up the sides of the trench, for a distance of about one or two inches on the mold. Then another layer 5 is deposited on top of the layer 3 to about half the height of the mold. Another layer 6 of concrete of a drier mix is 20 deposited on the layer 5 and completes the top of the pipe.

When the concrete has sufficiently set to 25 admit of the removal of the mold, the latter, which may be of a collapsible type, is withdrawn and placed end to end with respect to the pipe already formed. Such a mold is designated in Fig. 2 by the reference numeral 4, and may comprise a mechanical collapsible form or may have rubber or other kind of walls admitting of collapsing.

At the end of the pipe section from which the mold is withdrawn there is provided, in the event that the pipe is to withstand internal pressure, slip joint 8 (Fig. 2) comprising two telescoping members 9, 10, respectively, sufficiently tapered to permit telescoping or expansion without escape one from the other. At the end of one of the 40 slip joint members, say the member 9, there is provided a circumferential bead 11 to hold a ring 12 of oakum or other appropriate material.

That end of the laid pipe containing the 45 telescoping joint, before the joint is extended, is built thicker than the body of the pipe to accommodate the joint, while the trench, where the joints occur, is enlarged as indicated at 13 to reinforce the joint. Moreover, 50 additional reinforcement indicated at 14 is provided at each joint but independent of the slip joint, this reinforcement 14 occurring in both of the abutting pipe lengths, which latter, however, may be considered as 55 substantially integral since the slip is only sufficient to allow for a relatively minute expansion and contraction.

The body of the pipe is indicated at 15, and for all practical purposes is monolithic. 60 As the laying of the pipe proceeds, the ends progress in both directions until ultimately the ends come within a short distance of each other, say within about five feet, this being the assumption in Fig. 3. To 65 finish the pipe where so closely approaching,

there are provided two telescoping lengths 16, 17 capable of being collapsed to a greater extent than the distance between the ends of the pipe. The telescoping mold is contracted and the ends then introduced into the 70 approaching pipe ends, each of which has a ring 18 similar to the ring 8 and formed with a bead 19 to which is applied a packing 20 of oakum or similar material. Like the structure of Fig. 2, the ends of the pipe 75 lengths are enlarged and provided with reinforcements 21 similar to the reinforcements 14.

The telescoping members 16, 17 are designed to form a support for a finishing section 22 of concrete and are permanently embedded therein.

While the pouring of the pipe is progressing, each mold 4 is provided with a closure or bulk head 23, as shown at the right hand end of Figure 2, and in the slip joint, adjacent this bulk head, the member 10 is telescoped within the member 9. After the concrete has set, and before the next pouring is made, the bulk head 23 is removed and the member 10 is drawn out, so that it will become embedded in the next length of pipe when the latter is poured, the position after the pipe is completed being shown at the left hand end of Figure 2. As above explained, when the concrete is first poured, the ends of the sections abut, but in setting the concrete contracts sufficiently to leave a slight space between the ends sufficient to allow for subsequent expansion and contraction.

By forming pipe at widely separated localities with the sections proceeding in opposite directions toward the other sections, the progress of the work is very much more rapid than would occur if the pipe proceeded from one locality onward.

When the pipe is not intended to withstand considerable internal pressure but simply serves as a duct for conveying water, with the stream of water less than the capacity of the pipe, it is unnecessary to employ slip joints. The arrangement shown in Figs. 4, 5 and 6 is a feasible one. The trench 1 is provided with a layer 3 of concrete in the manner already described, and a collapsible mold 4 is set in place and slightly embedded in the layer 3. The layer 3 is succeeded by the layer 5, as shown in Fig. 8, and this layer at its upper end terminates short above shoulders 24 upon which are placed planks 25 which may substantially extend to the top of the trench. After the concrete has sufficiently hardened, the planks 25 are withdrawn, leaving the shoulders 24 exposed, and then the final batch of concrete, shown in Fig. 9 at 26, is poured, with the gap in the mold indicated at 27 in Figs. 7, 8 and 9, covered by a closure 28 to prevent the concrete from dropping into the mold, and

which closure 28 may be removed from the finished pipe at the same time that the form or mold 4 is removed.

When the approaching finished pipes have come within about ten feet of each other, a layer 3 is filled into the bottom of the trench and the collapsible mold 4 of full 10-ft. length is introduced into the ends of the pipes or laid so as to be supported at the ends by said pipes, a support of about one inch being enough. Then the second layer 5 is introduced, the mold 4 is withdrawn and the short mold 4^a of about half the length of the full mold is placed in position, after which that portion of the pipe corresponding to the short mold is completed, and as soon as the pipe has sufficiently hardened, the short mold is withdrawn through the space next to the end of the other finished pipe.

Now, the unfinished portion which is only about one-half the length of a standard length of pipe, is filled in or crowned with sections 29 preferably made of corrugated galvanized iron in the form of half cylinders to rest upon the tops of the layers 5 and intermediately overlap so that the corrugations serve as locking means. Then the final batch of concrete is applied and allowed to harden, permanently embedding the sections 29 and thereby completing the junction of the two long sections of pipe.

The planks 25 produce a step receptacle for the lower edge of the final batch of concrete 6, 26, forming the top of the pipe, and in the case of non-pressure pipe there is thus produced a strong and reliable joint not liable either to crack or to leak.

It has been heretofore proposed to employ a rubber tube supplied with air pressure to form a collapsible mold and such a mold may be used in the formation of the concrete pipe in accordance with the present invention. This being a known expedient, it is unnecessary now to enlarge on it.

To cure the pipe made in accordance with the hereinbefore described method, water should be turned into it after the necessary length of pipe is laid, say from one-half mile to a mile, not later than about fifteen days after it is laid and not sooner than forty-eight hours after any of it is built.

To keep the molds from floating up on the concrete as poured, two large flat rocks 29^a already referred to, and one of which is shown in Fig. 11, are embedded in the bottom of the trench and secured to the mold by a strand or strands of wire 30; and when the mold is contracted and pulled, these rocks are permitted to remain in the trench, being spaced about two feet from either end of the mold. This, however, is only necessary where the temperature prevailing during the formation of the pipe ranges from 60° F. down to 30° F. The rocks serve the function of anchors.

Where slip joints occur, the oiling treatment is employed to prevent sticking of the fresh concrete thereto. The slip joints may be dipped in coal tar or other substance to preserve them. The molds are painted with a mixture of oils before the concrete is poured on them. If desired, an extra thickness of cement may take the place of reinforcements.

In Fig. 12, reinforcements 31 of circumferential type are shown. These reinforcements are made of metal mesh of half cylindrical contour with the meeting edges formed into hooks, and the hooks of one reinforcement interlocking with those of the other lengthwise of the pipe. Such reinforcements are, however, not needed in pipe under 24 in. in diameter, for the method of making concrete pipe by adding extra concrete and making the walls of the pipe thicker according to pressure to be put on is cheaper than to reinforce with iron and is just as strong.

What I claim is:—

1. The method of laying concrete pipe, which consists in locating molds at distantly separated points, pouring concrete about the respective molds to produce lengths of pipe, then elongating the pipe thus formed in both directions by withdrawing and resetting the molds next to the pipe already formed and again pouring concrete about the reset molds in turn to prolong the pipe, and repeating the operation until the ends of the progressively prolonged pipe sections are brought nearly into juxtaposition, each pipe length at its free end being coated with an oily composition before the next length is poured, to prevent the two juxtaposed ends from knitting together, and finally coupling the adjacent ends of the pipe by a final pouring of concrete, so that the pipe forms one continuous substantially monolithic form.

2. The method of laying concrete pipe, which consists in locating molds at distantly separated points, pouring concrete about the molds successively to produce respective lengths of pipe, then prolonging the formed pipe in each direction by withdrawing and resetting the molds adjacent the end of the pipe already formed and again pouring concrete successively about the reset molds, and repeating the operation to each pipe end in turn until the approaching ends are brought nearly into juxtaposition, and finally coupling said ends together by a final pouring of concrete, the last pouring being about a mold which remains permanently in place, whereby a continuous pipe is formed which is substantially monolithic.

3. The method of expediting the formation and laying of concrete pipe and preventing injury to the pipe from expansion

and contraction, consisting in pouring a concrete mixture of suitable consistency about 5 molds located at widely separated localities in the line of the completed pipe, elongating the pipe by progressively and retrogressively continuing the formation of the pipe until the ends of the pipe are in close juxtaposition, and completing the pipe into a substantially monolithic whole also by pouring 10 the concrete, and providing slip joints interposed between the pipe sections formed by each pouring, whereby to avoid buckling and cracks in the length of the pipe due to expansion and contraction.

15 4. The method of laying concrete pipe which consists first in digging a trench of considerable length to permit starting the building of the pipe simultaneously at several distant points along the trench, locating 20 the molds in the trench at spaced intervals, forming sections of pipe about the molds by pouring a basic layer of a concrete mixture in the bottom of the trench underneath the molds, pouring another layer on top of the 25 first layer and extending part way up the sides of the molds, and then pouring a final layer drier than either of the other layers over the molds to form the top of the pipe, then withdrawing the molds of a previously 30 constructed section of the pipe after the concrete has set, then placing the molds at the ends of the completed pipe section and continuing the pouring of the concrete about the molds with the operation proceeding both 35 progressively and retrogressively until the intervals between the originally fomed pipe lengths are nearly closed, and then pouring the concrete to produce a junction pipe section bridging the interval between the juxtaposed elongated pipe ends, whereby there is 40 formed a substantially monolithic concrete pipe of any length.

5. The method of laying concrete pipe which consists first in digging a trench of 45 considerable length to permit starting the formation of the pipe at numerous relatively distant points along the trench, placing molds in the trench at spaced intervals,

forming the pipe about alternate molds spaced from each other, withdrawing the 50 molds after sufficient setting of the concrete, placing the molds at the ends of the completed pipe sections and continuing the pouring of the concrete about the molds until the intervals between the originally 55 formed pipe lengths are completed to an extent bringing the formed pipe ends into close approach, next pouring the concrete to produce a junction pipe bridging the interval between the juxtaposed elongated pipe 60 sections whereby there is formed a substantially monolithic concrete pipe of any length and including slip joints as a permanent part of the pipe structure between certain 65 ones of the sections of concrete pipe.

6. The method of laying concrete pipe which consists in producing the concrete pipe in mold lengths by pouring successive layers of concrete of sloppy mix which will flow without tamping about the bottom and 70 sides of the molds and finishing the pouring with a drier concrete mix which will absorb moisture from the lower concrete pourings and will avoid the running of water along the top of the formed concrete which would 75 injure new concrete, and prolonging the pipe progressively and retrogressively, and finally joining the prolonged pipe sections when near juxtaposition whereby the pipe from end to end is substantially monolithic. 80

7. The method of forming concrete pipe in a trench, which consists in providing anchors in the bottom of the trench, pouring in a layer of concrete of sloppy mix which is wet enough to flow without tamping, then setting 85 the mold and tying the same to the anchor to prevent the mold from being lifted by the hydrostatic pressure of the concrete, then pouring in another layer of the sloppy mix around the sides of the mold, and then completing the pouring of the pipe section by a layer of drier mix which will absorb water 90 from the lower layers.

In testimony that I claim the foregoing as my own, I have hereto affixed my signature.

THOMAS DE LA MARE.
